UNITED STATES PATENT OFFICE.

LEOPOLD S. SAMUEL, OF NEWARK, NEW JERSEY.

SOAP CAKE.

SPECIFICATION forming part of Letters Patent No. 790,319, dated May 23, 1905.

Application filed February 18, 1905. Serial No. 246,352.

To all whom it may concern:

Be it known that I, LEOPOLD S. SAMUEL, a citizen of the United States, residing at Newark, in the county of Essex and State of New Jersey, have invented certain new and useful Improvements in Soap Cakes; and I do hereby declare the following to be a full, clear, and exact description of the invention, such as will enable others skilled in the art to which it applies to make and use the same, reference being had to the accompanying drawings, and to numerals of reference marked thereon, which form a part of this specification.

This invention relates to certain improvements in soap cakes containing layers of compounds, medicaments, or matters other than soap serving to produce other useful effects while the detergent elements of the cake are operating.

The objects of the present invention are to secure a more uniform distribution of the medicament or other non-saponaceous compound throughout the cake, whereby it will more certainly and efficaciously contact with the skin in service, to prevent more effectively the formation of unfilled spaces within the cake, to enable the soap sections of the cake to hold non-soapy matter therebetween and the cake as a whole in condition for service for a longer preliminary period, and to secure other advantages and results, some of which may be referred to hereinafter in connection with the description of the parts.

The invention consists in the improved soap cake and in the arrangements and combinations of parts of the same, all substantially as will be hereinafter set forth, and finally embraced in the clauses of the claim.

Referring to the accompanying drawings, in which like numerals of reference indicate corresponding parts in each of the figures, Figure 1 is a plan of my improved soap cake. Fig. 2 is a plan of the inside of one of the sections thereof. Fig. 3 is a section through the shorter axis of the said cake, and Fig. 4 is a side elevation of said cake.

In said drawings, 5 6 indicate two saponaceous outer sections of the soap cake, and 7 indicates a compound, composition, or substance which differs materially from the composition

of the sections 5 6 in that said composition, compound, or substance contains very little or no saponaceous matter, or, if largely of saponaceous matter, it may be impregnated with a medicament, qualifier, or content by which it is given a characteristic materially different in efficiency from the characteristic or characteristics of the sections 5 6.

The part 7 may be wholly of one material—wax, for instance—especially if the soap cake is to be used for certain laundry purposes, or it may be of soap or other vehicle for a medicament, or, and preferably, it may be a cream-like composition containing more or less well-known matters capable of rendering the skin soft, clear, free from sores, &c., or otherwise in a healthy condition.

To enable the cream-like or other substance to be uniformly and quickly inserted between the sections 5 6, so that no open spaces will be formed due to the entrapping of air, haste of application, or otherwise, I have formed the sections as illustrated, the section 6 having male protuberances 8 8 at its inner side, which lie at opposite ends of the longer axis of the sections. Said protuberances 8 8 fit neatly into shallow recesses of a corresponding shape in plan formed in the section 5, as indicated in outline in Fig. 4, and thus the said sections come together at their ends; but intermediate of said ends and at the sides of the protuberances said sections lie apart to form a chamber for the intervening cream substance or other matter. Between said protuberances said cakes are perforated, as at 9, the walls of the perforations being slotted, as at 10, and inwardly flaring, as shown clearly in Fig. 3. The surface-walls of the chamber between the sections are also slotted, as at 11, to serve to increase the strength of union between the united parts. The sections 5 and 6 being thus formed, the same are individually spread with the creamy or plastic mass of matter 7, a quantity being applied to each of said parts somewhat more than is ample to fill the spaces in the perforations 9 and between the sections. Said sections are then pressed firmly together, the male protuberances entering the opposite recesses, so that the sections are guided and held in proper relation. The

creamy mass is forced into all the recesses and compacted by pressure, and the surplus matter flows out at the sides and through the perforations, whence it may be quickly removed. I am thus enabled to quickly obtain within the cake a solid mass of medicated matter throughout, which extends outwardly to the periphery of the cake both at its edge and at the flat center of the sides of the cake, where it is certain to freely contact with the hand in service, and all "blow-holes" are avoided.

Having thus described the invention, what I claim as new is—

- 15 1. The improved soap cake herein described, comprising two centrally-perforated sections, one having protuberances at the opposite ends of its inner side and the other having shallow recesses to receive said protuberances, and an intermediate mass of matter extending from the center of the cake to its side peripheral edges and into said perforations, substantially as set forth.
- 20 2. The improved soap cake herein de-

scribed, comprising two sections, one having 25 male protuberances to enter recesses in the other, and each having inwardly-flaring perforations and chambers extending to the edges of the cake and a plastic mass intermediate of said sections extending into said perforations and to the opposite edges of said cake, substantially as set forth.

3. The improved soap cake herein described comprising two sections, one having male protuberances to enter recesses in the 35 other, and each having inwardly-flaring perforations with slotted walls and chambers extending to the edges of the cake and a plastic mass intermediate of said sections extending into said perforations and to the opposite 40 edges of said cake, substantially as set forth.

In testimony that I claim the foregoing I have hereunto set my hand this 7th day of February, 1905.

LEOPOLD S. SAMUEL.
